(57) **CLAIM**

The ornamental design for a display screen with transitional graphical user interface for a propagation viewer application, as shown and described.

DESCRIPTION

FIG. 1 is a front view of a first image in a sequence for a display screen with transitional graphical user interface for a propagation viewer application;

FIG. 2 is a second image thereof;

FIG. 3 is a third image of thereof; and,

FIG. 4 is a fourth image thereof.

The appearance of the image transitions sequentially between the images shown in FIGS. 1 through 4. The process or period in which one image transitions to another forms no part of the claimed design. The outermost broken line rectangle illustrates a display screen and forms no part of the claimed design. The remaining broken lines and the dot-dash broken lines illustrate portions of the graphical user interface, and form no part of the claimed design.
